DESIGN FOR A CAMERA TRIPOD HEAD

Frederick R. Heward, San Francisco, Calif.

Application January 24, 1940, Serial No. 89,678

Term of patent 3½ years

To all whom it may concern:

Be it known that I, Frederick R. Heward, a citizen of the United States, residing at the city and county of San Francisco, State of California, have invented a new, original, and ornamental Design for a Camera Tripod Head, of which the following is a specification, reference being had to the accompanying drawing, forming part thereof.

Fig. 1 is a side elevation of the camera tripod head, showing my new design;

Fig. 2 is a similar elevation of the opposite side; and

Fig. 3 is a rear view of the same.

I claim:

The ornamental design for a camera tripod head, substantially as shown.

FREDERICK R. HEWARD.
